UNITED STATES PATENT OFFICE.

LEE P. HYNES, OF CHICAGO, ILLINOIS, ASSIGNOR TO RAILWAY UTILITY COMPANY, OF CHICAGO, ILLINOIS, A CORPORATION OF ILLINOIS.

VENTILATOR.

1,283,521.

Specification of Letters Patent.

Patented Nov. 5, 1918.

Application filed September 28, 1914. Serial No. 863,870.

To all whom it may concern:

Be it known that I, LEE P. HYNES, a citizen of the United States, residing at Chicago, in the county of Cook and State of Illinois, have invented certain new and useful Improvements in Ventilators, of which the following is a specification.

My invention relates more particularly to that class of ventilators which is designed to be attached to cars and which depend for their action upon movement of air with reference to the ventilator whether produced by the movement of the car or other construction carrying the ventilator or by the natural air currents or winds. My invention while particularly designed with reference to car construction is applicable also to stationary buildings, and when used in connection with the latter operates entirely by the air currents passing over and around the same. Various ventilators have been constructed for a similar purpose in which, as in the present case, the ventilating action is due to aspiration caused by passing air currents, an example of the prior constructions being shown in my Patent 1,077,078 of October 28, 1913. It is the purpose of the present invention to improve the constructions of the prior art in effectiveness and durability and to decrease the cost of manufacture thereof.

In Figure 1 I have shown in perspective a preferred form of my invention adapted to be applied to a vertical portion of a car such as the sash thereof. Fig. 2 is a fragmentary view of the construction shown in Fig. 1 on a transverse vertical plane; Fig. 3 a vertical section through a slightly modified form thereof; Fig. 4 is a section upon the line 4-4 of Fig. 3; Fig. 5 is a modification of the device which is adapted to be applied to the curved roof of a car; Figs. 6 and 7 transverse vertical sections of modifications thereof; Fig. 8 a plan view of a form of my invention which is particularly adapted to a horizontal surface or the roof of a car or similar structure; and Fig. 9 a central vertical section thereof.

The feature of my invention which is of paramount importance and is common to all the forms shown in the several views is that the aspirating edges of the device are struck up out of the sheet metal of which the walls of the ventilator are formed. By this construction the rigidity of the walls of the

ventilator is increased and it is also possible at slight expense to largely increase the extent of edge subject to wind action as compared to former structures.

Referring now to Fig. 1 the construction shown therein is in its general design similar to one of the constructions shown in my said patent. It comprises an attaching flange 11 which is secured about an opening in the upright wall of the car. A short horizontal flue 12 connects the flange with the boxlike body 13 of the ventilator which comprises imperforate end walls 14 which are or may be continuous with the end walls of the flue 11, a top 15 and a side wall 16, the latter of which are formed of sheet metal which is suitably slotted and struck up along one edge of each slit as at 17 to form an overhanging lip for the opening or slot. The number of slits and overhanging lips may be as desired or found most efficient. In the top wall or plate the lips are so struck up that the openings 19 face toward the car and are protected by said overhanging lips, which have the function not only of presenting aspirating advantages to passing air currents, as before described, but also prevent rain, dirt, etc., from being blown into the car. It will be noted from an inspection of the views that by reason of the struck-up lips it is impossible to blow a straight blast through the openings and into the flue 12 connected with the car (see particularly Fig. 3) and any water or the like which may light upon the floor 18 of the flue is permitted to drain outward through the open bottom of the ventilator.

In the construction shown in Figs. 1 and 2 a portion of the plane of the wall is retained between the slots as at 20 but in the modification as shown in Fig. 3 the inclined lip of one slot is continued to the edge of the next slot as at 21, the effect, however, being the same in both cases. The lower end of the ventilator is open except for a grille 22 formed of corrugated metal strips 23 fastened together at their abutting points as at 24. The grille which is best shown in Fig. 4 serves to break up upward currents of air and turn them toward the vertical so that they may escape through the openings in the side and top respectively of the ventilator.

Turning now to the construction shown in Fig. 5 it is seen to be substantially like Fig. 110

1 except that the duct or passage for communicating with the interior of the car is arranged to adapt it to be applied to the curved roof thereof. For this purpose the upper 5 wall or top of the ventilator is continued laterally and downwardly curved as at 25 and the attaching flange 26 is curved to adapt it to the curve of the roof.

In Fig. 6 is shown a modification similar 10 to Fig. 3 in the character of the aspirating wall and the lower opening but adapted like the modification shown in Fig. 5 to a curved roof.

In Fig. 7 is seen a further modification 15 in which the side wall is curved inwardly and continued practically to the outer edge of the flue 27 thus dispensing with the grille shown in Figs. 3, 4 and 6.

In Figs. 8 and 9 is shown a form of 20 ventilator adapted to be applied to the top of a car in which the flange 28 is formed with a rectangular upwardly projecting wall 29, terminating in an inwardly inclined flange 30. The top 31 of the ventilator is imperforate immediately above the opening into the car to prevent the direct entrance of rain, snow or dirt into the car and the ventilator is formed with four lateral, rectangular extensions 32, which, as shown, are 25 similar to the ventilator shown in Fig. 3 having the slotted struck-up walls 33, 34, the grille openings 35 and the imperforate end walls 36. The slots and lips, however, extend substantially from end to end of the 30 walls in which they are formed.

In each of the forms of the invention above-described are provided numerous aspirating edges and the total area of the ex- 35

haust openings is much greater than in the device of the prior art and at the same time ample provision is made to avoid the entrance of water, sand or dirt into the car by reason of the relation of the lips to the slots and to the opening into the car. The lips or overhanging edges are so placed with respect to the slots and with respect to the passage into the interior of the car that direct passage of water, dirt, or the like, is prevented and the slots in the top of the ventilator are vertically over the lower outlet so that any rain or the like entering said slots drops through the lower opening out of the ventilator. In order to further avoid side drafts carrying water and dirt into the car it will be noted that the openings on the side are directed upwardly toward the openings in the top so that any air blowing against the side and entering the ventilator passes outward at the top of the same.

I claim:

A ventilator for cars comprising a rectangular sheet metal structure having a lateral opening for communication with the interior of the car to be ventilated, imperforate front and rear walls, the bottom being open and the top wall slitted and struck up to form a series of substantially vertical openings therein, the edges of said openings remote from the side having the lateral opening being raised relatively to the other sides of said openings whereby the lateral opening is protected from the entrance of rain.

LEE P. HYNES.
